UNITED STATES PATENT OFFICE.

JAMES MACON DONALDSON, OF DODD CITY, TEXAS.

SAFETY HAT-PIN.

1,114,869.

Specification of Letters Patent. Patented Oct. 27, 1914.

Application filed November 29, 1912. Serial No. 734,161.

To all whom it may concern:

Be it known that I, JAMES MACON DONALDSON, a citizen of the United States of America, and resident of Dodd City, in the 5 county of Fannin and State of Texas, have invented certain new and useful Improvements in Safety Hat-Pins, of which the following is a specification.

This invention relates to personal wear 10 and an object of the invention is to produce a hat pin which will embody means for the protection of humanity against accidental or malicious injury, it being well recognized that hat pins that are now in common use 15 are injurious to those persons in proximity of the wearer.

A further object of this invention is to provide a hat pin having novel means for attaching the same to a hat through the action of mechanism applied to a hat and retained thereon while the pin is removable at the will of the user.

A still further object of this invention is to produce a hat pin and a guard therefor 25 which will prove ornamental, means being provided for securing a head on said pin and in providing novel means for preventing contact of metallic surfaces which might prove disadvantageous through the noise that 30 would be occasioned by their contact.

A still further object of this invention is to provide novel means for retaining the hat pin in place, said novel means comprising in part elements adapted to coact with and engage a pin for the purpose of holding it 35 against displacement until the parts are properly manipulated.

With the foregoing and other objects in view, the invention consists in the details of 40 construction and in the arrangement and combination of parts to be hereinafter more fully set forth and claimed.

In describing the invention in detail, reference will be had to the accompanying drawings forming part of this specification wherein like characters denote corresponding parts in the several views, and in which—

Figure 1 illustrates a sectional view of 45 fragments of a hat with the invention applied thereto; Fig. 2 illustrates a sectional view of my invention; Fig. 3 illustrates a view in elevation of a fragment of a pin showing one form of point; Figs. 4 and 5 illustrate similar views showing other forms 55 of points.

In these drawings 7 denotes a pin having

one end provided with threads 8 adapted to engage threads in a disk 9 which forms a fragment of the head, the said head comprising a semi-spherical ornamental head 10, 60 associated with the disk 9 and with a hollow section 11 forming a knob-like end for the pin. The hollow section 11 contains a yielding ring 12 which encircles the pin 7 and it is the object of the inventor that this ring 12 65 be slightly pressed within the section 11 so that it will produce sufficient friction to prevent accidental rotation of the head on the pin 7 and the dislodgment or disengagement of the head from the pin. 70

In order to produce an eye or aperture through which the pin may be inserted, the fragment 13 of the hat is apertured for the reception of a flange 14 formed centrally of the disk 15, the said flange 14 containing a 75 bushing 16 of rubber or the like to prevent contact of the pin with the flange 14, which flange is preferably of metal. An ornamental ring 17 is placed on the outer surface of the fragment 13 of the hat and acts as a 80 buffer for the head of the pin when in position or as an ornamental finish of the hat when the said pin is removed. As a means for retaining the pin in place, the opposite side of the hat from that just described is 85 provided with pin engaging members and guards, the same comprising in part two apertured disks 18 and 19, a convexed casing 20 having a flange 21 external of the hat and a casing 22 provided with a central opening 90 23 formed by the flange 24 internally of the hat, the said flange 24 extending through an aperture in the fragment 25 of the hat and producing an eye for the reception of the pin 7. 95

The flange of the casing 20, the disks 18 and 19 and a flange 26 of the inner casing 22 are secured together by means of fastenings 27 which may be of any appropriate type here shown in the form of rivets. 100

The pin 7 has, near its end remote from the head, an annular groove 28 adapted to receive a fastening for retaining it in position.

A modification of the pin is shown in 105 Fig. 4 in which said pin is identified by the numeral 32 in which the pin 33 is reduced as compared with the end of the pin shown in Fig. 3 although for all practical purposes a rather blunt point is efficient and preferable. 110

In Fig. 2, I have shown in detail mecha-

nism for retaining the pin in place. The plate 34 is provided with a guide 35 riveted or otherwise secured to the plate 34 by the securing means 36. The guide 35 is approximately C-shaped and confines the ring 39 which ring is adapted to enter the annular grooves 28 of the pin when applied thereto, the said ring serving to retain the pin against displacement owing to the fact that the ring is pressed upwardly into the groove through the action of the spring 40 which bears against the periphery of the disk, and serves to force it normally into the groove. The disk 39 may be displaced from engagement with the pin by means of the operating lever 41, which is mounted in a recess or seal 35^a of the guide 35 so that the lever may be manipulated for forcing the ring downward, whereas on releasing the said lever the spring 40 will serve to force the ring upwardly into the position shown in Fig. 2.

From an inspection of Fig. 2 it will be observed that when the pin 7 is forced into the aperture of the latch, said latch will be moved against the action of the spring 40 until the groove or annular channel 28 of the pin alines with the said latch, at which time the spring 40 will force the latch into the annular groove, thus retaining the pin against displacement until the handle 41

is manipulated for the purpose of moving the latch from the annular channel or groove at which time the pin may be withdrawn.

A safety hat pin made in accordance with this invention will be found efficient for the purpose of retaining the pin in place and as a measure of protection, as heretofore mentioned.

I claim—

A device for retaining hat pins, comprising a casing, an apertured plate within the casing, a disk having an aperture therein larger in diameter than the diameter of the pin adapted to register with the aperture in the plate, a spring bearing against the disk and holding it in engagement with the pin to prevent withdrawal of the pin from the casing, an approximately C shaped guide for the disk, said guide having a recess therein forming a seat, a lever having an end fulcrumed in the recess of the guide, said lever bearing against the disk and projecting through the casing for pressing said disk against the action of the spring.

In testimony whereof, I hereunto affix my signature in the presence of two witnesses.

JAMES MACON DONALDSON.
